UNITED STATES PATENT OFFICE.

JOHN H. J. HAINES, OF NEW YORK, N. Y., AND ALEXANDER B. FERNALD,
OF JERSEY CITY, NEW JERSEY.

ELECTRIC-ARC LAMP.

SPECIFICATION forming part of Letters Patent No. 544,578, dated August 13, 1895.

Application filed November 20, 1894. Serial No. 529,380. (No model.)

To all whom it may concern:

Be it known that we, JOHN H. J. HAINES, residing at New York, in the county of New York and State of New York, and ALEXANDER B. FERNALD, residing at Jersey City, in the county of Hudson and State of New Jersey, citizens of the United States, have invented a certain new and useful Arc Lamp, of which the following is a specification.

10 This invention relates to feeding mechanism for electric-arc lamps, and has for its object the construction of a feeding and a feed-regulating device which shall be constant and steady in its action, and which shall be operable upon a continuous-current circuit or upon an alternating-current circuit.

15

To this end my invention consists in the combination, with a screw-formed carbon-carrier held against rotation while allowed to reciprocate, of a nut on said carrier adapted to be freely rotated by the movement thereof, and provided with an extended friction-surface with which a friction-detent engages for the purpose of regulating the movement of 25 the carbon-carrier by effecting a gradual decrease in the rotation of the nut as it comes to rest upon a fixed support and a gradual increase in the rotation thereof as it is lifted from said support, thereby maintaining an even feed.

30

It also consists in the construction and combination of parts, as hereinafter described and claimed.

In the accompanying drawings, Figure 1 represents a side elevation, partially in section, of a lamp constructed to be operated upon an alternating-current circuit. Fig. 2 is a plan of said lamp. Fig. 3 is a partial sectioned side elevation taken at an angle of 35 40 ninety degrees from the position seen in Fig. 1. Fig. 4 is a horizontal section through the feeding mechanism of the lamp, taken in the plane, represented by the line 4-4 in Fig. 3. Fig. 5 is a side elevation of the same feeding mechanism applied to a continuous-circuit lamp. Fig. 6 is a plan of said lamp, the upper plate being removed. Fig. 7 is a perspective view of a detail of the feeding mechanism, as shown in Fig. 5.

45

50 In Figs. 1 and 4 of the drawings, 8 represents the base of the lamp, which may be made

of any suitable insulating material, but preferably of slate. From the base depends side rods 9, one of which, as usual, may be made hollow for the insertion of the conductor leading to the lower carbon. The lower-carbon holder is supported from a cross-piece joining said rods and may be of any suitable construction. It is here shown, however, as consisting of a clamp 7, screwed upon the end of 55 a bolt 6, passing through a boss in the cross-piece considerably larger than the bolt and insulated from said cross-piece at the top by a slate bushing 5 and at the bottom by an asbestos washer 4. A screw 3 is inserted in said 65 bolt for clamping the wire 2 leading to the lower carbon.

Upon the upper side of the base rests the frame for the feeding mechanism, which consists of the lower plate 10 and the upper plate 70 11, supported upon the posts 12. This frame is secured to the base of the lamp by means of the hollow bolt 13 and its nut 14. Through this hollow nut and the upper plate 11 passes the upper-carbon carrier or rod 15. To this 75 is attached the carbon-holder 16, of any preferred form. This carbon-carrier is screw-threaded throughout its entire length, which, thread is of a pitch sufficiently coarse to allow it to rotate by its own gravity through a nut 80 held stationary. Upon this screw-threaded rod is placed a nut, as 17, shown provided with a flange 18.

In practice the screw-threaded carrier, instead of rotating as it descends through the 85 nut, is held stationary by any suitable means, such as a spline and groove, while the nut is allowed to rotate, and by the regulation of the rotation of the nut the descent of said carrier is controlled. The spline and groove may 90 be arranged in any suitable manner, but we have shown the spline as formed in the hollow nut 13, as at 19, and the groove formed longitudinally of the carrier parallel to the axis thereof, as at 20.

95 For controlling the rotation of nut 13 any suitable restraining device may be employed other than the one shown, which is intended to operate by friction upon the flange 18. This device consists of a bar 21, supported 100 vertically and adapted to reciprocate through ways formed in the upper and lower plates

11 and 10, upon which bar are located projections 22 and 23, passing at either side of the flange 18. The bar 21 is moved by means of a lever 24, shown pivoted in lugs 25, depending from the upper plate 11. It passes through an aperture in bar 21, and is pivoted to the core 26 of magnet 27, here shown as a solenoid. At the opposite end of said lever is attached a counterbalancing-weight 28, and also one end of a dash-pot 29, which is pivoted at its other end to lugs rising from the lower plate 10. From this it will be seen that any movement of the core 26 will cause a movement of the bar 21. A suitable stop, as 30, is shown as connected to the posts 12 for limiting the upward movement of the nut 17, particularly at the time of trimming. In trimming, the manipulation of the feeding mechanism to release the upper-carbon carrier is usually effected by means of a rod 31, pivoted to the lever 24, and extending through an aperture in the base 8 to the under side thereof. The circuit of this lamp, as indicated in Fig. 2, is from the source of supply through magnet 27 to the frame, from the frame by brush 32 to the upper-carbon carrier, thence through the carbons to the insulated conductor extending through the hollow rod 9, and to the source of supply.

The operation of the feeding mechanism is as follows: Said mechanism being substantially in the position shown with the carbons together, the current on being turned on will draw core 26 down and bar 21 up, causing projection 23 from said bar to engage the under side of the flange 18, between which there will be sufficient friction to prevent the nut 17 from rotating, and so lift the carrier 15 until the proper length of arc is produced.

Then as the arc lengthens the core will rise from the magnet, the bar 21 will descend until the nut rests upon the surface of nut 13, when the further descent of bar 21 will lessen the friction between parts 23 and 18 sufficiently to allow the nut to rotate and the carrier to descend. When the proper length of arc is obtained the rod 21 will be slightly raised to check the rotation of nut 18. By the adjustment of weight 28 a proper balance of the parts is attained, and by the use of the dash-pot 29 the too sudden operation of the feeding mechanism is prevented. Projection 22 upon bar 21 acts as a limiting-stop to prevent, by engaging the upper surface of disk 18, the rapid whirling and consequent rise of nut 17 upon the carrier when the rapid descent of the carrier is stopped by the carbons coming together. In this way the nut is retained in proper position for immediate engagement by projection 23 upon an increase of current through the magnet, thus facilitating the striking of the arc. The rotation of nut 17 is also impeded when at rest upon nut 13 by the friction between it and nut 13.

In the trimming operation a rod 31, which is attached to lever 24 and passes down

through the base, is pushed up, causing bar 21 to descend and disengage the friction device from the nut, when the carbon-carrier 70 may be readily manipulated. When bar 21 is at its lowest point projection 23 rests upon the plate 10 and nut 17 upon nut 13, the flange 18 being at that instant free from engagement by either of projections 22 or 23. 75

In the continuous-current-circuit lamp shown in Figs. 5 and 6 the feeding mechanism is more simple than that already described. In this lamp the magnet 33 may be variously located, but is here shown secured to the upper plate, in which position its core 34 tends to fall out of the magnet. To this core is pivoted a lever 35, which is split to pass the carbon-carrier 15, and is pivoted at 36 in a bracket 37 upon the post 38. The short end of lever 85 35 passes into an aperture formed in the reciprocating bar 21, whose lower guide is in bracket 37 and whose upper guide is in a bracket 39 upon post 38. In this lamp magnet 33 is shown in a shunt-circuit, the main 90 circuit of the lamp being from a source of supply to the frame of the feeding mechanism, thence by brush 32 to the carbon-carrier 15 through the carbons and back to the source through the insulated wire in rod 9, the shunt 95 extending from the brush through the coil of magnet 33 to the insulated conductor as it leaves rod 9.

The operation of this lamp is as follows: The parts of the feeding mechanism being in 100 position substantially as shown, with the carbons separated, the current being turned on, it is obvious will be through the shunt-exciting magnet 33, which on drawing up its core will tilt the lever 35, lower rod 21 until 105 nut 17 rests upon nut 13, and rod 21 upon descending a little farther will disengage projection 23 from flange 18 and come in contact with the lower plate 10 before projection 22 can strike flange 18, thereby leaving nut 17 to rotate, with no other hinderance than the friction between it and nut 13. As the current then flows through the main circuit, core 33 will gradually descend, bringing projection 23 into engagement with flange 110 18, thereby preventing the rotation of nut 17 and lifting the nut and carbon-carrier as said core descends. When the arc begins to lengthen the core will again be gradually drawn up and the upper carbon fed down. 115 In this lamp I also provide a rod 31 connected to lever 35 or to the core 34, so that by pushing said rod upwardly the restraint upon nut 17 may be released and the carrier easily manipulated. The means for retarding the rotation 120 of nut 17 may be greatly varied in form, location, and operation without departing from the gist of the invention involved in this feature, which resides in a suitable detent, clamping device, friction device, or like restraining means acting upon nut 17 to govern its rotation and so regulate the feeding 125 of the upper carbon and assist in striking the arc. We have shown this special plan of

feeding as adapted to the two principal forms of arc lamps, but do not lay any stress upon the location of the controlling-magnet or the manner of inserting the same in the circuit of the lamp.

In the shunt shown in Fig. 5 any of the usual forms of cut-out may be used, the insertion and operation of which are well understood by electricians, and are therefore not shown.

What we claim as our invention is—

1. In an electric arc lamp, the combination with a carbon carrier in the form of a reciprocating non-rotating screw, of a nut rotated by the reciprocation of the carrier and provided with an extended flange, a fixed support upon which said nut may rest during the free descent of the carrier, a reciprocating friction detent adapted to engage said flange near its periphery, and means for regulating the engagement between said detent and flange so as to effect a gradual decrease in the rotation of said nut as it is lifted from its fixed support and to effect a gradual increase in its rotation as it is lowered upon said support, as and for the purpose set forth.

2. In an electric arc lamp, the combination with a carbon carrier in the form of a reciprocating non-rotating screw and a nut rotated by the reciprocation of said carrier and provided with a flange, of a reciprocating bar connected to and operated by the controlling magnet of the lamp, a projection upon said bar for engaging one surface of said flange for lifting the nut and carrier, and another projection on said bar for engaging the opposite surface of said flange to limit the rise of the nut on the carrier, as and for the purpose set forth.

3. In an electric arc lamp, the combination with a carbon carrier in the form of a recip-

rocating non-rotating screw and a nut rotated by the reciprocation of said carrier and provided with a friction surface, of a reciprocating bar provided with a projection for engaging said friction surface, and a lever pivoted to the frame of the lamp and connected to said bar and to the movable part of the controlling magnet of the lamp, substantially as and for the purpose set forth.

4. In an electric arc lamp, the combination with a carbon carrier in the form of a reciprocating non-rotating screw and a nut rotated by the reciprocation of said carrier and provided with a friction surface, of a reciprocating bar provided with a projection for engaging said friction surface, a counterbalanced lever pivoted to the frame of the lamp and connected to said bar and to the movable part of the controlling magnet, and a dashpot connected to said lever, as and for the purpose set forth.

5. In an electric arc lamp, the combination with the base, of a frame for the feeding mechanism, a hollow bolt connecting said base and frame and provided with a spline on its inner surface, a carbon carrier in the form of a screw passing through said bolt and provided with a groove extending longitudinally thereof to receive said spline, a nut free to rotate upon said carrier, and means for regulating the rotation of said nut, substantially as set forth.

Signed at New York, in the county of New York and State of New York, this 17th day of November, A. D. 1894.

JOHN H. J. HAINES.
